ELECTRICAL CONNECTER

Carlo Salvati, Brooklyn, N. Y.

Application July 29, 1932. Serial No. 625,604

6 Claims. (Cl. 200—115.5)

This invention relates to electric connectors or the like and more particularly to connectors provided with a plurality of fuses which may be successively used to bridge one of the circuit lines.

It is usual to place fuses in the line of an electric circuit only where such a fuse would control a number of outlets. For this purpose the most common type of fuse is the plug type which required changing when "blown out". It is also well known to use a fuse plug to control such a circuit in which a plurality of fuses are successively brought into the circuit. It is obviously a disadvantage to have one fuse control a plurality of outlets since all the outlets are rendered inoperative when the trouble, which lies in one of them, blows the fuse.

It is therefore an important object of the invention to provide an electric connector in which a plurality of fuses may be successively brought into the circuit and which is adapted for use in an individual circuit of for instance, a floor lamp, radio, toaster outlet, etc.

Another object of the invention is to provide an electric connector of this character which is of simple and durable construction and in which, by a simple partial turn of a cap, one of several fuses in the form of a cartridge may be brought into the circuit.

Further objects and advantages of the invention will appear from the following disclosure thereof together with the attached drawing which illustrates a preferred form, and in which:

Fig. 1, is a longitudinal sectional view of a preferred embodiment of the invention.

Fig. 2, is a bottom plan view of the rotating member.

Fig. 3, is a plan view of the stationary portion.

The connector body 5 of dielectric material may be of substantially cylindrical form and be provided with a central opening 6. The body is preferably also arranged with a plurality of circular passages 7 arranged circumferentially and equally spaced adjacent the outer wall of the body. The passages 7 are adapted to receive fuses 8 in the form of cartridges of any well known form. These cartridges as here shown are provided with metallic caps such as 9—9'.

A base portion 10 of substantially round contour, may be provided with a peripheral flange 11 for engagement with one end of the body 5 and a cap portion 12 of similar contour may have a flange 13 for engagement with the other end of the body.

The base 10 is arranged with a pair of contact

members in the form of projecting prongs or contactors 14 and 15. The prong 14 is embedded in the dielectric material of the base and has electrical connection such as at 16 with a plate 17 nested in the inner portion of the base.

There is preferably struck from the plate 17, a plurality of contact fingers 18 equal in number to the number of fuse cartridges and these are struck up to such a degree as to have engagement within the respective passages 7 of the body.

The prong 15 is fixed to the base plate 10 by means such as the rivet 19 and has an inreaching portion 20 terminating in a spherical end 21. The spherical end is positioned over the exact center of the base plate 10.

The cap 12 which may be provided with a knurled or roughened periphery carries a pair of spring contact members or plug connectors 22 and 23, the member 22 being secured to the cap by means such as the rivet 24 provided with a contact bead 25 and the member 23 being secured to the cap by the rivet 26, the bead of which is countersunk below the inner face of the cap.

The contact member 23 is provided with a branch portion 27 terminating in a socket member 28 adapted to engage the spherical end 21.

The cap 12 is further provided with openings 29 receptive of the prongs of a standard electric attachment plug and these openings are preferably in registerable alignment with the spring contact members 22 and 23.

As can be seen from the foregoing an electric connector is provided in which any one of the fuse cartridges 8 may be positioned to bridge the terminals 14 and 22. Should the cartridge 8 be positioned "blow-out", a simple partial turn of the cap will bring the adjacent cartridge into the bridging position.

When all the fuses are "blown-out", the connector may be separated by disengaging the spherical end 21 from the socket 28 and the "blown" fuses replaced. The end 21 and socket 28 may then be re-engaged by an end-wire push on the base 10 and cap 12.

Inadvertent rotation between the body 5 and base 10 is prevented by the keying action of the portions 18 in the passages 7 and these portions are slightly resilient to insure good electric contact between the head 25 and cartridge end 9 and cartridge end 9' and contact fingers 18.

From the foregoing it will be seen that a simple device for the purpose has been disclosed in the preferred form of its embodiment but it is not desired to restrict the details to

the exact construction shown, it being obvious that changes, not involving the exercise of invention, may be made without departing from the scope of the appended claims.

5 Having thus described my invention what I claim as new and desire to secure by Letters Patent, is:

1. An electric connector comprising a body housing, forming a shell, having a wall of substantial thickness, a plurality of fuse cartridges located within said wall, a base closure covering one end of said housing, means to interconnect at said closure one terminal each of all of the fuse cartridges, a rotatable, removable closure at the other end of said housing, means on said removable closure to contact, one at a time, the second terminal of the fuse cartridge, plug connectors on the removable closure and contactors protruding from the base closure, one of said contactors and plug connectors to serve as terminals for one of said fuses and the other of said contactors to connect with the remaining plug connector.

2. An electric connector comprising a body housing forming a shell, a plurality of fuse cartridges interchangeably located within the wall of said housing, a base closure covering one end of said housing, means to interconnect at said closure one terminal each of all of the fuse cartridges, a rotatable, removable closure at the other end of said housing, means on said removable closure to contact, one at a time, the second terminal of the fuse cartridges, plug connectors on the removable closure and contactors protruding from the base closure, one of said contactors and plug connectors to serve as terminals for one of said fuses and the other of said contactors to connect with the remaining plug connector and means to flexibly connect the remaining connector with said other connector.

3. An electric connector comprising a body housing confining an empty space within the walls thereof, a plurality of fuse cartridges located within said wall, a base closure covering one end of said housing, means to interconnect at said closure one terminal each of all of the fuse cartridges, a rotatable, removable closure at the other end of said housing, means on said removable closure to contact, one at a time, the second terminal of the fuse cartridges, plug connectors on the removable closure and contactors protruding from the base closure, one of said contactors and plug connector to serve as terminals for one of said fuses and the other of said contactors to connect with the remaining plug connector, said plug connectors being located within the empty space of said housing.

4. An electric connector comprising a body housing having a shell, having a wall of sub-

stantial thickness, a plurality of fuse cartridges located within said wall, a base closure covering one end of said housing, means to interconnect at said closure one terminal each of all of the fuse cartridges, a rotatable, removable closure at the other end of said housing, means on said removable closure to contact, one at a time, the second terminal of the fuse cartridges, plug connectors on the removable closure and contactors protruding from the base closure, one of said contactors and plug connector to serve as terminals for one of said fuses and the other of said contactors to connect with the remaining plug connector, said plug connectors to extend from the end of the fuses near the movable closure downward in the direction towards the base closure.

5. An electric connector comprising a body housing having a wall of substantial thickness within which is confined an empty space, a plurality of fuse cartridges interchangeably located within said wall, a base closure covering one end of said housing, means to interconnect at said closure one terminal each of all of the fuse cartridges, a rotatable, removable closure at the other end of said housing, means on said removable closure to contact, one at a time, the second terminal of the fuse cartridges, plug connectors and contactors protruding from the base closure, one of said contactors and plug connectors to serve as terminals for one of said fuses and the other of said connectors to connect with the remaining plug connector, said plug connectors to extend from the end of the fuses near the movable closure downward in the direction towards the base closure within the empty space of said housing.

6. An electric connector comprising a body housing, confining an empty space within the walls thereof, a plurality of fuse cartridges located within said wall, a base closure covering one end of said housing, means to interconnect at said closure one terminal each of all of the fuse cartridges, a rotatable, removable closure at the other end of said housing, means on said removable closure to contact, one at a time, the second terminal of the fuse cartridges, plug connectors on the removable closure and contactors protruding from the base closure, one of said contactors and plug connectors to serve as terminals for one of said fuses and the other of said contactor to connect with the remaining plug connector, said plug connectors being located within the empty space of said housing, said plug connectors to extend from the end of the fuses near the movable closure downward in the direction towards the base closure within the empty space of said housing.
